(57) **CLAIM**

The ornamental design for a stand for monitor, as shown and described.

DESCRIPTION

1. Stand for monitor

Figure 1.1 is a front, top and right side perspective view of a stand for monitor;

Figure 1.2 is a rear, top and right side perspective view thereof;

Figure 1.3 is a front elevation view thereof;

Figure 1.4 is a rear elevation view thereof;

Figure 1.5 is a left side elevation view thereof;

Figure 1.6 is a right side elevation view thereof;

Figure 1.7 is a top plan view thereof;

Figure 1.8 is a bottom plan view thereof;

Figure 1.9 is another left elevation view shown in a state of use and an alternate position;

Figure 1.10 is another rear, top and right side perspective view shown in a state of use;

Figure 1.11 is another rear, top and right side perspective view shown in a state of use and an alternate position;

Figure 1.12 is another rear, top and right side perspective view shown in a state of use and an alternate position;

Figure 1.13 is another rear, top and right side perspective view shown in a state of use and an alternate position;

Figure 1.14 is another top plan view shown in a state of use; and

Figure 1.15 is another left side elevation view shown in a state of use and an alternate position.

The broken lines shown in Figures 1.1-1.9 illustrate portions of the stand for monitor that form no part of the claimed design. The broken lines illustrating the monitor in Figures 1.10-1.15 are environment, while the remaining broken lines in Figures 1.10-1.15 illustrate portions of the stand for monitor that form no part of the claimed design.

1 Claim, 15 Drawing Sheets
